CLAIM

The ornamental design for a protective headgear, as shown and described.

DESCRIPTION

FIG. 1 is a front perspective view of a first embodiment of a protective headgear showing our new design; FIG. 2 is a left side elevational view thereof; FIG. 3 is a right side elevational view thereof; FIG. 4 is a rear elevational view thereof; FIG. 5 is a front elevational view thereof; FIG. 6 is a top plan view thereof.

FIG. 7 is a bottom plan view thereof; FIG. 8 is a front perspective view of a second embodiment of a protective headgear showing our new design; FIG. 9 is a left side elevational view thereof; FIG. 10 is a right side elevational view thereof; FIG. 11 is a rear elevational view thereof; FIG. 12 is a front elevational view thereof; FIG. 13 is a top plan view thereof; and, FIG. 14 is a bottom plan view thereof.

The broken lines and portions contained within depict portions of the protective headgear that form no part of the claimed design.

1 Claim, 14 Drawing Sheets
